INVENTOR
Herbert M. Knight

UNITED STATES PATENT OFFICE.

HERBERT M. KNIGHT, OF MONTCLAIR, NEW JERSEY.

SUBSURFACE TILE.

Application filed September 22, 1920. Serial No. 411,954.

To all whom it may concern:

Be it known that I, HERBERT M. KNIGHT, a citizen of the United States, and resident of Montclair, in the county of Essex and 5 State of New Jersey, have invented certain new and useful Improvements in Sub-surface Tiles, of which the following is a specification.

My invention relates to tile for sub-soil 10 uses and more particularly to tile for use in sewage disposal irrigation where the tiles are placed beneath the surface of the ground for sub-surface purification purposes.

15 Among the objects of my invention are, the providing of tiles that shall be economical in construction. Another object is to provide a combination of tile that shall give a large percolative distribution area.

20 A further object of the invention is to provide a combination of tile that shall admit of raising one tile above the surface of the lower tile. Other objects of the invention will be disclosed hereafter.

25 I secure these objects by means of the appliances herein described and illustrated in the accompanying drawings wherein Fig. 1 is a cross section of a sub-surface tile on the line 1—1 of Fig. 2; Fig. 2 is a section of such a tile on the line 2—2 of Fig. 1; Fig. 3 is a cross section of a tile on the line 3—3 of Fig. 2; Fig. 4 is an isometric view of the upper member of such a tile and Fig. 5 is an isometric view of the lower 35 member of such a tile.

Referring to drawings, similar figures refer to similar parts.

(1) is an upper tile of a sub-surface irrigation tile system; (2) is a lower tile of such a system; (3) are cavities in the lower member of such a system; (4) is the cavity created by super-imposition of the upper member upon the lower member; (5) are transverse ribs on the upper surface of the lower member; (6) are depressions created by the transverse ribs (5); (7) are longitudinal side beads and (8) are openings in said side beads; (9) is an aperture left between the ends of the upper members 45 and (10) are apertures left between the lower members.

While the accompanying drawings illustrate a practical application of my invention, it is not intended to limit the invention 55 to the arrangement disclosed, such disclosure being for the purpose of illustration

only and not exclusive of other forms or arrangements in which the invention may be embodied.

In a system of sub-soil irrigation, one of 60 the desirable features is to gain a large area of distribution for percolation purposes. The usual method of construction of a sub-soil irrigation system is to use a tile as a lower member with a plain upper 65 surface, upon which upper surface rests either a horseshoe or similar shaped upper member. The discharge of a septic tank or siphon chamber enters the upper member and finds outlet through the apertures 70 between the upper members and also through the apertures between the lower members and from thence into the soil. The distribution thereof is practically confined to the apertures between the ends of 75 the upper, and the apertures between the ends of the lower members.

This invention seeks to distribute the liquid flowing through the upper member from the septic tank or siphon chamber 80 so that it shall be discharged from beneath the upper member as well as into the lower member thus making the discharge more uniform and preventing the clogging of 85 the soil at the few points of percolation provided at the apertures between the upper and the lower members. This object is secured by casting upon the lower member small transverse ribs which are located between side beads which are raised above the 90 upper portion of the lower members. In these side beads are apertures or weirs through which in addition to the material discharged from beneath the upper member, the liquid flowing in the upper member is dis- 95 charged into the soil. It is seen from this description that an opening exists beneath the feet of the upper member leaving a space through which the liquid can be discharged from the upper member over the side beads 100 into the soil. The depression in the roof of the upper member created by the side beads and the transverse ribs is filled with liquid 105 which drains out through the weirs or openings in the beads. It is thus seen that by the super-elevation of the upper member, with a space between it and the lower member, and discharge openings along the bottom of said upper member and through the openings in the side bead of the lower member, a better distribution of the liquid 110 is secured, a more rapid flow results, and

that the purifying effect of the soil is greater due to a more uniform distribution of the liquid, as compared with the concentrated flow when the discharge is largely 5 confined to the apertures between the tiles. The system illustrated is equally applicable to a filtration system in which the tile are used as collectors instead of distributors, the super-elevation of the open tile upon 10 and above the upper surface of the lower tile serving to produce a more uniformly distributed and also an augmented flow.

What I claim is:

- 15 1. A tile, longitudinal ducts in said tile, a top covering said ducts, sides outwardly enclosing said ducts, upwardly extending longitudinal ridges projecting above said top and notches in said ridges.
- 20 2. A tile, longitudinal ducts in said tile, a top covering said ducts, sides outwardly enclosing said ducts, upwardly extending longitudinal ridges in linear alinement with said sides projecting above said top, and notches in said ridges.
- 25 3. A tile, longitudinal ducts in said tile, a top covering said ducts, sides outwardly enclosing said ducts and transverse ribs projecting above said top.
- 30 4. A tile, longitudinal ducts in said tile, a top covering said ducts, sides outwardly enclosing said ducts, upwardly extending longitudinal ridges projecting above said top, and transverse ribs projecting above said top.
- 35 5. A tile, longitudinal ducts in said tile, a top covering said ducts, sides outwardly enclosing said ducts, upwardly extending longitudinal ridges in linear alinement with said sides projecting above said top, and transverse ribs projecting above said top.
- 40 6. A tile, longitudinal ducts in said tile, a top covering said ducts, sides outwardly enclosing said ducts, upwardly extending longitudinal ridges projecting above said top, notches in said ridges, and transverse ribs projecting above said top.
- 45 7. A tile, longitudinal ducts in said tile, a top covering said ducts, sides outwardly enclosing said ducts, upwardly extending longitudinal ridges in linear alinement with said sides projecting above said top, notches in said ridges, and transverse ribs projecting above said top.
- 50 8. A tile, longitudinal ducts in said tile, a top covering said ducts, sides outwardly enclosing said ducts, upwardly extending longitudinal ridges projecting above said top, transverse ribs projecting above said top, and notches in said ridges positioned between adjacent transverse ribs.
- 55 9. A tile, longitudinal ducts in said tile, a top covering said ducts, sides outwardly enclosing said ducts, upwardly extending longitudinal ridges in linear alinement with said sides projecting above said top, transverse ribs positioned between adjacent transverse ribs, and a supported tile having a non-continuous periphery, superimposed above and resting upon said transverse ribs.

verse ribs projecting above said top, and notches in said ridges positioned between adjacent transverse ribs.

10. A tile, longitudinal ducts in said tile, 70 a top covering said ducts, sides outwardly enclosing said ducts, upwardly extending longitudinal ridges projecting above said top, transverse ribs projecting above said top and a depression enclosed by said ridges and said ribs.

11. A tile, longitudinal ducts in said tile, 75 a top covering said ducts, sides outwardly enclosing said ducts, upwardly extending longitudinal ridges projecting above said top, transverse ribs projecting above said 80 top, a depression enclosed by said ridges and said ribs, and means for draining said depression.

12. In a system of sub-surface tiles, the 85 combination of a tile having longitudinal ducts therein, a top covering said ducts, transverse ribs projecting above said top, and a tile having a non-continuous periphery, superimposed above and resting upon said transverse ribs.

13. In a system of sub-surface tiles, the 90 combination of a tile having longitudinal ducts therein, a top covering said ducts, transverse ribs projecting above said top, and a tile having a non-continuous periphery composed of rectilinear faces angularly disposed with an interior angle between adjacent faces greater than a right angle, superimposed above and resting upon said transverse ribs.

14. In a system of sub-surface tiles, the 95 combination of a supporting tile having longitudinal ducts therein, a top covering said ducts, transverse ribs projecting above said top, and a supported tile having a non-continuous periphery, the un-enclosed portion of said supported tile being in juxtaposition to said supporting tile, said supported tile resting upon said transverse ribs.

15. In a system of sub-surface tiles, the 100 combination of a supporting tile, longitudinal ducts in said tile, a top covering said ducts, sides outwardly enclosing said ducts, upwardly extending longitudinal ridges projecting above said top, transverse ribs 115 projecting above said top, notches in said ridges positioned between adjacent ribs, and a supported tile having a non-continuous periphery, said supported tile being superimposed upon and supported by said ribs.

16. In a system of sub-surface tiles, the 110 combination of a supporting tile, longitudinal ducts in said tile, a top covering said ducts, sides outwardly enclosing said ducts, upwardly extending longitudinal ridges in 120 linear alinement with said sides projecting above said top, transverse ribs projecting above said top, notches in said ridges positioned between adjacent ribs, and a supported tile having a non-continuous periphery, 125

said supported tile being superimposed upon and supported by said ribs.

17. In a system of sub-surface tiles, the combination of a supporting tile, longitudinal ducts in said tile, a top covering said ducts, sides outwardly enclosing said ducts, upwardly extending longitudinal ridges in 20 5 projecting above said top, transverse ribs projecting above said top, notches in said ridges positioned between adjacent ribs, and a supported tile having a non-continuous periphery, said supported tile being superimposed upon and supported by said ribs, the un-enclosed portion of said tile being in 25 10 15 juxtaposition with said ribs.

18. In a system of sub-surface tiles, the combination of a supporting tile, longitudi-

nal ducts in said tile, a top covering said ducts, sides outwardly enclosing said ducts, upwardly extending longitudinal ridges in 20 25 linear alignment with said sides projecting above said top, transverse ribs projecting above said top, notches in said ridges positioned between adjacent ribs, and a supported tile having a non-continuous periphery, said supported tile being superimposed upon and supported by said ribs, the un-enclosed portion of said tile being in juxtaposition with said ribs.

Signed at New York in the county of 30 New York and State of New York this twenty-first day of September A. D. 1920.

HERBERT M. KNIGHT.
